UNITED STATES PATENT OFFICE.

NAPOLEON B. DOUGLASS, OF BERKELEY, CALIFORNIA.

WALL-BED.

1,180,112.

Specification of Letters Patent. Patented Apr. 18, 1916.

Application filed March 28, 1912. Serial No. 686,847.

To all whom it may concern:

Be it known that I, NAPOLEON B. DOUGLASS, citizen of the United States, residing at Berkeley, in the county of Alameda and 5 State of California, have invented new and useful Improvements in Wall-Beds, of which the following is a specification.

This invention relates to wall beds, and pertains especially to a wall bed arrangement by which a full-sized double bed may be so mounted in a closet having a door of ordinary width, that this bed can swing in and out of the closet through an arc of 180° without interference with or from the door.

10 The object of the present invention is to provide a wall bed mounting in which a bed is mounted at one side of a wall opening and adjacent to the butt edges of the door which usually forms a closure for the 20 opening; no part of the weight of the bed however being carried by the door; there being employed in conjunction with this door a panel on the bed mounting, co-acting with the door to give finish to the structure 25 and to avoid clumsy, cumbersome and unsightly construction, all as will be herein-after explained.

The invention consists of the parts and the combination and construction of parts 30 as hereinafter more fully described and claimed, having reference to the accompanying drawings, in which—

Figure 1 is a side elevation in partial section, showing the invention. Fig. 2 is a 35 plan view in partial section through the closet and door, showing the invention; the bed being disposed in the closet as shown in full line, the dotted lines indicating the bed partially reversed. Fig. 3 is a view similar 40 to Fig. 2, with the parts in reverse position.

A is a closet or recess normally closed by the door 2, which is hinged at 3. This door is an ordinary stock door. 4 is a full-sized, double bed, considerably wider than the 45 door, and mounted on a bed-carrying bracket frame 5, so as to be turned in a vertical plane and stand in either of the two positions indicated in Fig. 1.

The invention resides in the manner of 50 mounting the bed in the closet and independent of the door, so far as the latter carrying any weight is concerned, so that when the door is opened the bed may swing to complete reversal in either direction, through 55 an arc of 180°.

The bed-carrying structure 5 is mounted

on a vertical standard or tube section 6, which is rigidly connected to two bracket arms 7 at top and bottom; each of these arms having pintles 8 suitably stepped in 30 the top and bottom of the door opening and approximate to the hinges 3 of the door, but in no wise connected with the door, or the door jamb. The arms 7 and standard 6 are placed to one side of the center of the bed 65 where a wide bed is used, a sufficient distance to allow the proper clearance of the bed with the door frame when the bed is reversed.

In order to cause the bed to turn in unison with the door 2 I prefer to connect the edge of the bed-carrying structure 5 with the edge of the door on the side which is within the closet, by a toggle or jointed link 9. In order to completely close the closet 75 opening when the bed is opened out for use I attach a panel 10 to the back of the bed-carrying frame and I may hinge a small door 11 to the opposite door jamb, as shown at 12; this small door being adapted to open 80 outwardly from the interior of the closet and form a joint with the adjacent edge of the panel 10, when the parts are in the position shown in Fig. 3. This small door affords easy access to the closet. 85

When the bed is in the closet as shown in full lines Fig. 2, access may then be had to the closet by simply opening the door 2 and swinging the parts in to the dotted line position indicated. 90

By the mounting of the bed on the frame formed by the arm 7 and standard 6, and pivoting the arm 7 as shown at 8, I do away with all reversing links and simply swing the bed in a true circle about the 95 pivots 8, as a center; it being understood that the frame 5 which carries the bed is rigid on the standard 6 and that the latter is rigidly connected with the arm 7. The length of the arm 7 is sufficient to allow the 100 bed to stand in vertical planes parallel with the closet wall, irrespective of whether the bed is in the closet or out of it. 105

From the foregoing it will be observed that the crank arms 7 are vertically pivoted 110 to one edge of the closet opening and adjacent to the butt edges of the door 2; the door carrying no part of the weight of the structure. The panel 10 on the bed frame is complementary to the door 2; being adapted to stand in continuation of and in the same plane with the door when the parts are

opened in the position shown in Fig. 3. When the door is fully closed the panel 10 stands behind the wall in the closet and out of the plane of the door 2 when the latter is closed. The panel 10 is necessary not only to give finish and form a back-ground or wall against which the bed has the appearance of being shoved up against when out for use, but it forms a barrier or wall 10 against drafts. The door 2 and panel 10 forms a combination and mechanical movement novel and peculiar in the wall bed business and has resulted in the increased economy in manufacture and reduction of 15 space necessary for manipulation.

Having thus described my invention what I claim and desire to secure by Letters Patent is—

The combination with a receptacle having 20 a door opening and a door hinged at one edge to the side wall of the opening for closing the latter, of a bed frame greater in

width than said door opening, a vertically arranged shaft having upper and lower crank arms rigidly connected to the shaft 25 with the free ends of said arms pivotally mounted in top and bottom bearings in the door opening, whereby said shaft may be swung into and out of the receptacle, and a rigid connection between the bed frame and said shaft located on one side of the vertical center of the bed frame, whereby the bed frame and shaft form a substantially rigid structure which may be swung in unison 30 into and out of the receptacle through a door opening of less width than the bed frame. 35

In testimony whereof I have hereunto set my hand in the presence of two subscribing witnesses.

NAPOLEON B. DOUGLASS.
